To all whom it may concern:

Be it known that I, Simeon Kenneth Peeples, a citizen of the United States, residing at Wichita, Kansas, have invented a new, original, and ornamental Design for a Louvered Corrugated Metal Awning, of which the following is a specification, reference being had to the accompanying drawing, forming a part thereof.

Figure 1 is a three-quarter front perspective view of an awning embodying the new design.

Figure 2 is an end view of the awning illustrated in Figure 1.

Figure 3 is an enlarged sectional view taken laterally through two adjacent corrugations and louvers illustrating more particularly the louver design which constitutes an important feature of the overall awning design.
